Inventor:
Louis Tomchin,
By his Attorney, Leo McLean

UNITED STATES PATENT OFFICE.

LOUIS TOMCHIN, OF BROOKLYN, NEW YORK.

WATCH.

1,382,256.

Specification of Letters Patent. Patented June 21, 1921.

Application filed August 12, 1920. Serial No. 402,939.

To all whom it may concern:

Be it known that I, LOUIS TOMCHIN, a citizen of the United States, and a resident of the borough of Brooklyn, county of 5 Kings, city and State of New York, have invented certain new and useful Improvements in Watches, of which the following is a specification.

My improvements are applicable to 10 watches generally, but especially to those of relatively small size such as used as pendants on necklaces, etc., and for use on wristlets,—the main object of the invention being to adapt the same watch for use for 15 either purpose named. In other words I produce an interchangeable watch in the sense that it is alternately convertible into a wrist watch, or into a pendant for neck wear, according to preference, the transposition being effected by simple means susceptible of convenient manipulation; and the 20 invention consisting in the specific combination and arrangement of parts described and claimed,—the distinctive feature being the provision of detachable coupling devices 25 whereby the watch may be made fast, alternately and successively, to flexible connections adapting it either for wrist or neck wear, according to circumstances or requirements, as hereinafter fully set forth.

In the accompanying drawings,

Figure 1, is a front elevation of my improved watch, illustrating its use as a pendant for neck wear;

Fig. 2, is a front elevation of the same watch illustrating its incorporation in a wrist band;

Fig. 3, is a side view of the watch;

Fig. 4, is a rear view of the watch face plate, removed;

Fig. 5, is a front view of the watch without its face plate, and with the casing partly broken away to show the peripheral coupling shoulders;

Fig. 6, is a front view of one of the auxiliary coupling devices;

Fig. 7, is a side view thereof;

Fig. 8, is a rear view of the cover plate thereof;

Fig. 9, is an end view thereof; and Fig. 10, is a front elevation of one of said auxiliary coupling members, without its cover plate.

The watch W, is mounted in a works frame 55 or casing C, in a manner well known in the

art,—C', being the usual face plate fitting over the front of said works frame.

Peripherally the casing C, is formed with a plurality of differently positioned shoulders c, c, for engagement with interlocking 60 mechanism constituting part of each of the auxiliary coupling devices A, A, which latter are preferably, although not necessarily, identical in form and construction, so that when both are attached to the watch casing 65 C, as in Figs. 2 and 5, a uniform bilaterally symmetrical appearance will result.

As shown particularly in Fig. 5, of the drawings, the peripheral coupling shoulders c, c, are formed on three sides of the casing 70 C, so that the watch W, can be used either as a pendant to a necklace ribbon or other means of suspension N, as indicated in Fig. 1, or may be interposed between the ends of the wrist band B, as indicated in the 75 aforesaid Fig. 2.

In the drawings, for convenience, the watch casing C, is shown as of octagonal configuration peripherally, although it may obviously be of round, square, or of any 80 other circumferential shape without departing from the spirit and intent of my invention in this respect, the essential feature being the provision of the plurality of differently positioned peripheral coupling 85 shoulders c, c, on the casing C, so correlated as to afford means whereby the watch may be attached on opposite sides, by means of duplicate coupling members A, A, to a lateral band, as B, in Fig. 2, or by means of 90 the single coupling member A, in engagement with the intermediate coupling shoulders, as in Fig. 1, as a pendant to a necklace or equivalent N, as in Fig. 1. In this connection it may be noted that the watch 95 stem w, protrudes from the lower or fourth side of the casing C, diametrically opposite to the coupling shoulders c, c, used in connection with a coupling member A, for suspending the watch as a pendant to a flexible 100 neck loop; and that the numerals on the watch dial are inverted as viewed in the drawings, but nevertheless are in proper position for convenient observation by the wearer, whether worn on neck or wrist.

As adjuncts to each watch W, thus mounted in a suitable peripherally shouldered casing C, it is designed to provide two auxiliary coupling devices A, A, provided with latch mechanism adapted to interlock with the 110

coupling shoulders c, c , on the casing, and these coupling members may be duplicates in shape and construction, or otherwise, as may be found most expedient, the essential 5 feature in this respect being a plurality of coupling devices forming part of the watch set or kit, whereby the watch is rendered interchangeable and convertible either into a wrist watch, or into a pendent for neck 10 wear, as set forth.

Hence, while I herein show and describe coupling devices A, A , which are duplicates in form and construction, I do not limit myself in this particular, since obvious 15 mechanical equivalents and expedients may be resorted to with like result. With this understanding, a , represents the base plate, and a' , the cover plate of one of my auxiliary coupling devices, either of which plates 20 may be formed with the loop a^2 , for connection with the necklace or ribbon N , or with the wrist band B . Fulcrumed on the stud a^3 , of the base plate a , are the twin latch levers l, l , between the latch arms l', l' , of 25 which is interposed the expansible spring s , which tends constantly to separate the levers and thrust them against the flanged sides of the base a , as shown in Fig. 10, with the ends of their finger arms l^2, l^2 , protuberant 30 and accessible as means for manually manipulating the latch levers against the resistance of the spring s , for the purpose of locking or releasing the latch hooks l^x, l^x , as related to the peripheral coupling shoulders 35 c, c , on the casing C , of the watch W . Thus when the latch hooks are interlocked with

the coupling shoulders c, c , of the casing as shown in Fig. 5, the spring s , insures positive copulation between the said interlocking parts until both latch levers l, l , are retracted simultaneously against its resistance 40 sufficiently to clear the hooks l^x, l^x , from contact with said shoulders c, c .

By my invention of detachable auxiliary coupling members forming essential parts of 45 the watch outfit, I render the watch duplex in function, and obviate the necessity for duplication, which is especially advantageous where the more expensive grades of 50 watches are concerned.

What I claim as my invention and desire to secure by Letters Patent is,

In combination, a watch of the character designated, a casing therefor formed with diametrically opposed peripheral shouldered recesses and with an intermediate peripheral shouldered recess, the exterior edges of said recesses being flat and extending in planes transversely at right angles to the central axis of the watch, and detachable interchangeable auxiliary coupling devices formed with flat bases abutting against the said flat edges on the peripheral recesses in the watch casing, and with pivotally crossed spring latch levers adapted to engage with said 55 shouldered recesses in the watch casing, for the purpose described.

LOUIS TOMCHIN.
